UNITED STATES PATENT OFFICE.

FRED C. AREY, OF OAK PARK, ILLINOIS.

EXPANDED-METAL-LATH MACHINE.

1,384,376.

Specification of Letters Patent. Patented July 12, 1921.

Application filed January 27, 1919. Serial No. 273,302.

To all whom it may concern:

Be it known that I, FRED C. AREY, a citizen of the United States, and a resident of the city of Oak Park, in the county of Cook 5 and State of Illinois, have invented certain new and useful Improvements in Expanded-Metal-Lath Machines; and I do hereby declare that the following is a full, clear, and exact description of the same, reference being had to the accompanying drawings, and to the numerals of reference marked thereon, which form a part of this specification.

This invention relates to an improved form of an expanded metal lath machine 15 wherein mechanisms are provided to so cut and expand a sheet of metal that the completed lath embraces a plurality of sections, formed with adjacent sections expanded in different directions and separated from each 20 other by depressed ribs or reinforcing channels.

It is an object of this invention to provide an improved expanded metal lath machine adapted to produce expanded lath 25 having integral unexpanded ribs separating the expanded portions.

It is also an object of the invention to provide a lath machine wherein cutters are 30 adapted to cut a sheet of metal so that the cut sections are separated by plain uncut sections, and with the cuts in adjacent cut sections disposed in different directions.

Another object of the invention is to provide a lath machine wherein a sheet of metal 35 is first cut, then expanded and then shaped to rib the plain longitudinal portions which separate the expanded sections of the sheet of metal.

A further object of the invention is to construct a lath machine having arbors provided with spiral cutters positioned to so 40 cut a sheet of metal passed therebetween that a plain strip of metal is left between each two adjacently disposed sections which have 45 the cuts therein directed in different directions.

It is furthermore an object of the invention to construct a lath machine provided 50 with cutters, guides, expanders and formers adapted to successively act upon a sheet of metal to produce a finished lath wherein

a plurality of parallel longitudinally disposed channel ribs are formed to separate the cut sections which are expanded in different directions.

Another object of the invention is the construction of a lath machine wherein a pair of arbors are provided with spaced cutters embracing spaced diagonally disposed blades adapted to cut a sheet of metal to permit the 60 same to be expanded and formed to produce a lath wherein adjacently disposed cut sections are expanded in different directions and are separated by depressed integral ribs.

It is an important object of this invention 65 to provide a lath machine of effective construction adapted to successively cut, expand, form and straighten out finished expanded metal laths wherein uncut reinforcing ribs separate the cut sections which are 70 expanded in different directions.

Other and further important objects of this invention will be apparent from the disclosures in the specification and drawings.

The invention (in a preferred form) is 75 illustrated in the drawings and hereinafter more fully described.

On the drawings:

Figure 1 is a rear side elevation of an expanded metal lath machine embodying the 80 principles of this invention.

Fig. 2 is a top plan view thereof showing the ends of the metal lath broken away.

Fig. 3 is a front side elevation of the machine.

Fig. 4 is an enlarged sectional view taken on line 4—4, of Fig. 2.

Fig. 5 is an enlarged sectional view taken on line 5—5, of Fig. 2.

Fig. 6 is an enlarged transverse sectional 90 view taken on line 6—6, of Fig. 2, showing parts in elevation.

Fig. 7 is a sectional view, with parts in elevation, taken on line 7—7, of Fig. 4.

Fig. 8 is a section taken on line 8—8, of 95 Fig. 4, with parts shown in elevation.

Fig. 9 is a section taken on line 9—9, of Fig. 4, with parts shown in elevation.

Fig. 10 is an enlarged fragmentary detail section taken on line 10—10, of Fig. 5, with 100 parts omitted.

Fig. 11 is an enlarged fragmentary plan

view of two groups of cutters separated by a spacer.

Fig. 12 is a detail side view of one of the groups of cutters and spacers mounted on an arbor shown in section.

Fig. 13 is an end view of one of the arbors.

Fig. 14 is an enlarged fragmentary detail section of the cutter blades of two co-acting cutters acting upon a piece of metal.

Fig. 15 is an enlarged detail side elevation of one of the cutter blades.

Fig. 16 is an enlarged detail side elevation of one of the cutter blade spacers.

Fig. 17 is a top plan view of a fragmentary portion of a sheet of metal after it has been cut, showing the first step in the operation.

Fig. 18 is a side view of the cut sheet of metal as it is being expanded.

Fig. 19 is a sectional view taken on line 19-19, of Fig. 18.

Fig. 20 is a top plan view of the finished expanded metal lath.

Fig. 21 is a transverse sectional view thereof.

As shown on the drawings:

The reference numeral 1, indicates a long base or foundation, provided with an extension 2, formed on the rear side and near the intake end thereof. A driving shaft or axle 3, is disposed transversely of the base 1, and above the base extension 2, and has the inner end thereof rotatably journaled in the upper end of a standard or support 4. The outer end of the driving shaft 3, is rotatably supported in a bearing 5, formed upon a large standard or support 6, which is securely mounted longitudinally of the machine upon the base extension 2. Rotatably mounted upon the driving shaft 3, is an idler pulley 7. Keyed or otherwise secured upon the driving shaft 3, adjacent the idler pulley 7, is a driving pulley 8.

Also keyed upon the driving shaft 3, to the outside of the driving pulley 8, is a pinion 9, which meshes with a large gear 10. The large gear 10, is keyed upon a transverse shaft or axle 11, near the rear end thereof and adjacent the inner surface of the standard 6. The rear end of the shaft 11, is journaled in a bearing 12, formed on the upper portion of the standard 6. Said shaft 11, is also rotatably supported at its middle and front end in the lower halves 13, of standards, supports or frames, two of which are rigidly mounted upon the base 1, at the entrance or intake end of the machine. Rigidly bolted to the lower frame members 13, are upper frame members 14, which rotatably support a transverse shaft 15.

Each of the frame members 13 and 14, is provided with a rectangular opening and said openings register with each other when the upper and lower frame members are

assembled, to form vertical mounting slots or openings 16. Mounted in each of the frame slots 16, is a lower bearing block 17, and an upper bearing block 18. Projecting transversely through the frame members 13, and adjustably seated in the bottom of said frame slots 16, is an adjusting wedge or gib 19, the rear end of which is bent downwardly to form an arm 20, through which an adjusting screw 21, is threaded to engage in a threaded aperture provided in one of the lower frame members 13. A locking nut 22, is provided on said adjusting screw 21, to hold the gib locked in an adjusted position. The under surfaces of the lower blocks 17, are cut at an angle to co-act with the wedge portions of the gib 19. Threaded downwardly through the top of each of the upper frame members 14, are a plurality of adjusting screws 23, having the inner ends thereof threaded into threaded openings in the upper surfaces of the upper blocks 18. Adjustment of the gib 19, and the screws 23, permits raising or lowering of the blocks 17 and 18, in the frame slots 16.

Journaled in the lower blocks 17, and in the upper block 18, is a lower and an upper arbor respectively. Said arbors are constructed exactly alike but are mounted in inverted parallel relation to one another, as clearly shown in Fig. 6. Each arbor comprises a long bearing portion 24, an integral flange ring or collar 25, formed at the inner end of the bearing portion 24, and a middle portion 26, provided with a plurality of longitudinal ribs 26*. Said ribbed middle portion has integrally formed axially thereon a short bearing portion 27, having the inner portion adjacent the ribbed middle portion threaded, to removably receive threaded thereon a clamping ring or collar 28, provided with clamping bolts or screws to hold the same locked in position to securely hold cutter mechanisms clamped in position on the ribbed middle portions of the arbor.

Mounted upon each arbor are six groups of cutters, each represented as a whole by the reference numeral 29. Said cutters are separated from each other by spacing collars or rings 30, having the sides thereof notched as denoted by the reference numeral 31, to receive the cutters interlocked therewith. Half spacing collars 32, are disposed to the outside of the two end cutters, and have the outer surfaces thereof disposed adjacent the inner surfaces of the flange ring 25, and the clamping ring 28. The cutters 29, are arranged so that the cutting blades of adjacent cutters are disposed in different directions as clearly shown in Figs. 6 and 11. Each cutter 29, embraces a plurality of cutter segments or blades 33, each a little greater than a half circle and having a plurality of

spaced teeth 34, integrally formed on the inner peripheral edge thereof. Radial slots 35, are provided on each side near the outer margin of each cutter segment, and said radial slots 35, are arranged with those on one side staggered with respect to those on the other side. The cutter segments are engaged spirally around the ribbed middle arbor portion 26, with the teeth 34, engaging 10 in the grooves formed between the arbor ribs 26*. The cutter segments are separated one from the other by means of spacing segments 36, each a little greater than a half circle and of a diameter less than that of the 15 cutter segments 33. A pair of oppositely disposed integral teeth 37, are formed on the inner peripheral edge of each of the spacing segments 36, and said teeth are adapted to lockingly engage in certain of the grooves of 20 the ribbed middle portion 26, of an arbor to properly position the spacing segment to separate two of the cutter segments. The notched portions 31, of the spacing rings 30, are adapted to receive the ends of the cutter 25 segments and the spacing segments seated therein to form a snug fit, as clearly shown in Fig. 11. The cutters 29, of the upper and lower arbors are disposed to co-act with each other so that the cutting segments 33, of a 30 lower cutter are offset with respect to the cutting segments of a cutter disposed thereabove with which it is to co-act as shown in detail in Fig. 14.

Keyed upon the bearing portion 24, of the 35 lower arbor and to the outside of the front frame member 13, is a gear 38, which meshes with another gear 39, keyed upon the front end of the shaft 11. Keyed upon the end of the portion 24, of the upper arbor is a gear 40, which is in mesh with a gear 41, secured upon the shaft 15, to the outside of the rear frame 13—14. The gear 41, receives its drive from a gear 42, with which it meshes. Said gear 42, is keyed or otherwise secured 45 on the shaft 11, below the gear 41. Mounted securely upon the shaft 11, to the outside of the gear 42, is a spiral gear 43, which is in mesh with a spiral pinion or gear 44, mounted upon one end of a main shaft 45, 50 which is longitudinally disposed upon the machine base 1, toward the rear edge thereof and rotatably supported by means of suitable uprights or bearing standards 46, mounted on the base 1. Keyed to the middle portion of the main shaft 45, is a spiral pinion or gear 47, and a similar spiral pinion or gear 48, is mounted upon the other end of said shaft 45.

Securely mounted upon the base 1, about 60 midway between the ends thereof is a pair of supporting frames or walls 49. Supported by the frames 13—14, and the frames 49, are a pair of parallel longitudinally disposed sills or beams 50, to which a table 51, 65 is secured. Rotatably supported in the sills

50, between the frames 13—14, and frames 49, is a transverse shaft or axle 52, having a sprocket wheel 53, mounted upon the rear end thereof. A pinion 54, is mounted upon the front end of the shaft 52, and meshes 70 with a pinion 55, keyed upon a shaft 56. The shaft 56, is journaled in a yoke frame 57, which is pivotally mounted upon a transverse axle 58, supported by uprights 59, mounted on the sills 50. A guide roller 60, 75 is mounted on the shaft 56, between the arms of the yoke frame 57. Heavy controlling springs 61, are mounted upon the yoke frame 57, and are connected to the sills 50, to permit the roller 60, to yieldably engage 80 against and guide metallic lath moving through the machine over the table 51. A roller 62, is mounted upon the shaft 52, and projects upwardly above the table 51, to coact with the roller 60, to afford suitable 85 guides for the metal lath as it moves through the machine between said rollers 60 and 62.

The frames 49, are provided with suitable openings which open through the top of the frames and are closed by top plates or bars 90 63. The first slots or openings in the frames 49, are inclined toward the discharge end of the machine, and have mounted therein lower bearing blocks 64, for rotatably supporting a transverse shaft 65, upon 95 which a guide roller 66, is mounted between the frames 49. Disposed within the inclined opening above the lower blocks 64, are upper bearing blocks 67, for rotatably supporting a transverse upper shaft 68, having a guide 100 roller 69, thereon between the frames 49. The upper blocks 67, are adapted to be adjusted by means of adjusting bolts 70, which thread through the bars 63, and engage said blocks 67. A gear or pinion 71, is secured 105 on the front end of the upper shaft 68, and meshes with a gear or pinion 72, mounted on the front end of the lower shaft 65. A sprocket wheel is mounted upon the rear end of the lower shaft 65, and has engaged 110 therearound a continuous driving chain 73, which also is trained around the sprocket wheel 53, on the shaft 52. A spiral gear or pinion 74, is also secured on the rear end of the shaft 65, and is in mesh with a spiral gear or pinion 75, keyed upon the upper end of an inclined shaft 76, rotatably supported 115 on the outer or rear surface of the rear frame 49.

Mounted in the middle openings of the 120 frames 49, are lower bearing blocks 77, which rotatably support a transverse lower shaft 78. Securely mounted upon the shaft 78, are a plurality of forming wheels 79, having the periphery cut or formed to provide continuous V-grooves 80. The grooved forming wheels 79, are separated by spacing collars 81. A gear 82, is engaged on the front end of the shaft 78, and meshes with a gear 83, mounted upon the front end of an upper 130

- shaft 84, which is journaled in upper bearing blocks 85, disposed within the middle openings of the frames 49, above the lower blocks 77. Adjusting bolts 86, are threaded through the bars 63, and engage said upper blocks 85. A plurality of forming wheels or disks 87, are mounted upon the upper shaft 84, and have the periphery thereof beveled from the center toward both sides to permit said wheels 87, to co-act and interfit with the lower grooved forming wheels 79. The upper forming wheels 87, are separated from each other by spacing collars 88, as clearly shown in Fig. 8. A spiral gear 89, is keyed upon the rear end of the lower shaft 78, and said spiral gear meshes with a middle spiral gear or pinion 90, keyed upon the inclined shaft 76. Also keyed upon the inclined shaft 76, below the spiral gear 90, is a driving spiral gear 91, which meshes with the spiral gear 47, on the main shaft 45. Disposed in the third or deepest set of openings in the frames 49, are lower bearing blocks 92, which rotatably support a lower transverse shaft 93. A spiral gear 94, is keyed upon the rear end of said lower shaft 93, and meshes with a spiral gear 95, secured upon the lower portion of the inclined shaft 76. Secured upon the lower shaft 93, are three small V-grooved forming wheels 96, separated from one another by spacing collars or rings 97. A small gear 98, is keyed upon the front end of the lower shaft 93, and is in mesh with a large gear 99, secured upon the front end of an upper transverse shaft 100. The upper shaft 100, is journaled in upper bearing block 101, disposed above the lower blocks 92. Secured upon the upper shaft 100, are three large forming wheels 102, which have the periphery thereof beveled toward both sides to permit said large wheels to co-act or interfit with the small grooved forming wheels disposed therebelow. The large forming wheels 102, are separated from each other by spacing collars 103. Adjusting bolts 104, are threaded through the bars 63, and engage the upper blocks 101, to permit adjustment of said blocks. Securely mounted upon the base 1, at the discharge end of the machine are two supporting frames or standards 105, spaced apart and having angle brackets 106, mounted thereon. Brackets 106, are also secured to the frames 49. Supported on the angle brackets 106, are four parallel forming rails 107, having the upper surfaces thereof provided with V-grooves. The forming rails are disposed between the forming wheels 102, and above the spacing collars 97. The forming rails 107, span the space between the frames 49, and the frames 105. Rotatably mounted upon the frames 105, is a transverse shaft 108, having a spiral gear 109, keyed upon the rear end thereof to mesh with the spiral driving gear 48, on the main shaft 45. Secured upon the shaft 108, are seven forming wheels 110, provided with rounded circumferential grooves 111. The grooved forming or shaping wheels 110, are separated from each other by spacing collars 112. Integrally formed on the top and near the inner ends of each of the frames 105, is a pair of upright supports or lugs 113, for pivotally supporting one end of an arm 114. Journaled in the other ends of the two parallel arms 114, is a transverse shaft 115, having seven male forming wheels 116, secured thereon and separated from each other by spacing collars 117. Each male forming wheel 116, has a rounded bead or rib 118, integrally formed centrally on the periphery thereof to engage in one of the rounded grooves of the female forming wheels 110, as shown in Fig. 9. A gear 119, is keyed upon the front end of the shaft 115, and is adapted to mesh with a gear 120, keyed upon the front end of the lower shaft 108. Rotatably supported by the two frames 105, are a plurality of lower straightening rollers 121, disposed parallel to each other in a horizontal plane and each having a pinion 122, secured on the rear end thereof. Rotatably mounted on the outer side of the rear frame 105 are four auxiliary pinions 123, each of which is disposed to mesh with two of the pinions 122, as clearly shown in Fig. 1. Keyed upon the front end of the first roller shaft 121, is a pinion 124, which meshes with an intermediate driving pinion or gear 125, which engages with the gear 120. A large supporting block or casting 126, is disposed above each of the frames 105, and is adjustably connected with the frame 105, by means of two adjusting screws 127, which project through the block and thread into the frame therebelow. A bevel pinion 128, is secured upon the upper end of each of the adjusting screws 127, and meshes with a bevel gear 129, rotatably supported on an elbow bracket 130, one of which is integrally formed or rigidly secured upon the top and near each end of the block 126. Each bevel gear 129, is provided with a hand wheel 131, to permit manual rotation thereof for turning the screws 127, to raise or lower the blocks 126. Four parallel rollers 132, disposed in a horizontal plane, are rotatably supported by the two adjustable blocks 126. The rollers 132, are disposed above the rollers 121, and are staggered with respect thereto. Each upper straightening roller 132, has a pinion 133, secured upon the rear end thereof. Three auxiliary pinions 134, are rotatably mounted on the outer or rear side of the rear frame 105, in a position above the pinions 133, two of which mesh with each of said auxiliary pinions 134. Keyed upon the front end of 1

the first roller shaft 132, is a pinion 135, which is adapted to mesh with the pinion 124, to receive a drive therefrom.

Mounted above the free end of each of the 5 arms 114, is a controlling spring mechanism 136, the rod of which is connected to the frame 105, therebelow to afford a means whereby the shaft 115, is adapted to give slightly during the operation thereof if 10 necessary.

The operation is as follows:

Figs. 17 to 21, inclusive, show the various steps in the forming of the expanded metal lath produced by the lath machine herein- 15 before described. A sheet of metal 137, fed into the machine, as shown in Fig. 1, is first conducted between the upper and lower groups of cutters 29, which are operated through the driving gears connected up 20 with the driving shaft 3, which is operated by shifting a power belt from the idler pulley 7, to the driving pulley 8. The cutters, the guide rollers, the rib forming and expanding mechanisms and the straightening 25 devices are all simultaneously operated from the driving pulley 8, through the shaft 11, and the main shaft 45, to the spiral gears of which the various mechanisms of the machine are connected as already described.

30 The machine being in operation the sheet of metal 137, is drawn through the cutters which act to cut the metal as shown in Fig. 17, so that a plurality of longitudinal cut sections 138 and 139, are formed separated 35 from each other by plain uncut strips 140. The cut sections 138 and 139, are alternately disposed with respect to each other across the lath and have the cuts thereof inclined in different directions with respect to the 40 side edges of the lath, due to the arrangement of the cutter segments 33, of the cutters 29. By referring to Fig. 14, it will be seen that as the lath is conducted between the upper and lower cutters 29, parts 45 of the lath indicated by the reference numeral 141, are adapted to be bent as they engage in the radial slots 35, of the cutter segments 33. The parts 141, are therefore not cut by the cutters.

50 The lath is therefore cut as shown in Fig. 17, and is conducted over the table 51, and between the guide rollers 60 and 62, which also serve to straighten the cut lath. The upper roller 60, is permitted to swing upwardly about the shaft 58, and said roller 60, through the action of the spring mechanisms 61, is adapted to be held in contact with the upper surface of the lath. The guide rollers 60 and 62, are operated by 55 means of the chain 73.

The cut lath is next conducted to the rib forming and expanding mechanisms disposed about in the middle of the machine. From the table 51, the cut lath is fed between 60 the guide rollers 66 and 69, from which

point the cut lath is directed downwardly at an angle, as shown in Fig. 4, and is fed between the rib forming wheels 79, and 87, which are so spaced that they engage below and above alternate plain strips 140, of the 70 cut lath, and act to shape said plain strips into V-channels 142, as shown in Fig. 19. The V-channelled and cut lath is then conducted through the expanding portion of the machine with the first, third, fifth and seventh 75 V-ribs or channels 142, engaging in the V-grooves of the horizontal rails 107, while the second, fourth and sixth plain margins, engage under the large forming wheels 102, and above the small grooved wheels 96, as 80 clearly shown in Fig. 7. This arrangement causes the cut sections 138 and 139, to be drawn or expanded downwardly as denoted by the reference numeral 143 and produce the longitudinal corrugations 142^a as shown 85 in the lower part of Fig. 19.

From the forming and expanding devices the lath is drawn upwardly and spread outwardly, as shown in Fig. 2, and is conducted between the finishing forming wheels 90 110, and 116. The beads 118, engage in the V-grooves of the rib portions 142, and press the same into the rounded grooves 111, to form the grooved rounded reinforcing ribs 144, which are integral with and separate 95 the expanded portions or sections 145, and 146, of the finished lath. The expanded sections 145 and 146, are alternately disposed across the lath and are expanded in different directions due to the peculiar cutting of the 100 cut sections 138 and 139. From the rib forming wheels 110 and 116, the lath is fed between the sets of staggered straightening rollers 121 and 122, which serve to straighten 105 out the lath to produce the finished expanded reinforced metal lath shown in Figs. 20 and 21.

The various cutting, guide, forming and expanding devices are adapted to be adjusted to receive lath of different thicknesses. 110 The adjustment of the various devices is adapted to be made through the respective adjusting screw and screw bolts, and is believed to be self-evident.

I am aware that numerous details of construction may be varied through a wide range without departing from the principles of this invention, and I therefore do not purpose limiting the patent granted otherwise than necessitated by the prior art. 120

I claim as my invention:

1. The combination with a lath machine, of rotatable arbors forming a part thereof, spacers on said arbors, and a plurality of 125 diagonally positioned cutter segments securely disposed between each pair of said spacers to form cutters adapted to act upon a metal sheet to diagonally cut slots in parallel longitudinal sections of said metal sheet leaving plain sections separating the cut 130

- sections, said cutters being positioned so that the slots in two sections separated by a plain section are diagonally directed in different directions.
5. 2. In a lath machine the combination with a pair of adjustably mounted arbors, spacing collars secured on each thereof, and cutters separating the spacing collars from each other, each of said cutters comprising a plurality of slotted cutter segments disposed spirally around said arbors, and spirally positioned spacer segments separating said cutter segments.
3. In a lath machine the combination with 15 a pair of arbors, mechanisms for rotating the same, longitudinal ribs integrally formed on the middle portion of each of said arbors, notched spacing collars engaged on the ribbed middle portion of each of said arbors, 20 and cutters separating said spacing collars one from the other, each of said cutters embracing a plurality of radially slotted cutter segments disposed spirally around said arbors and interfitting with the ribs thereof, 25 and spirally positioned spacer segments separating said cutter segments and also interfitting with said arbor ribs.
4. In a lath machine the combination with a driving mechanism, of a pair of arbors 30 driven thereby, ribs integrally formed lon-
- gitudinally on the middle portion of each of said arbors, spiral cutters on each of said arbors interfitting with the ribs thereof, notched spacing collars separating said spiral cutters and interfitting with said spiral cutters and with said arbor ribs, and means for securely clamping said spiral cutters and said spacing collars in position.
5. A metal cutting mechanism comprising a plurality of spirally arranged cutting elements having supporting serrated surfaces, a shaft having a corresponding serrated surface for co-operating therewith, and spirally arranged spacing elements having lugs for co-operating with said serrated shaft and arranged between said cutting elements.
6. A metal cutting mechanism for cutting diagonal slots, comprising a plurality of substantially semi-circular cutting elements spirally arranged, spacing elements between said cutting elements, and a supporting member interlocked with said elements.

In testimony whereof I have hereunto subscribed my name in the presence of two subscribing witnesses.

FRED C. AREY.
